UNITED STATES PATENT OFFICE

OLIVER J. HOWE, OF BROCKTON, MASSACHUSETTS, ASSIGNOR TO DANIEL C. REBHUN,
OF CINCINNATI, OHIO

SHOE-TREE

Application filed March 9, 1929. Serial No. 345,735.

The present invention relates to shoe trees or forms, and more especially to improvements in adjustable trees for retaining or restoring the shapes of boots or shoes.

5 The primary object of the invention, is to provide a sectional shoe tree with means whereby the sections may be moved relative to each other so as to fit shoes of varying sizes.

10 A further object comprehends the provision of simple and efficient means for maintaining the shoe sections in predetermined adjusted positions.

15 Another object consists in providing a locking plunger that is so positioned as to extend slightly beyond a cut-out portion in the upper surface of the heel section of the tree, so that the plunger will not project beyond the upper surface of the tree, and thus materially facilitate the packing or wrapping of 20 the shoe tree especially when travelling.

Other objects and advantages of the invention will become apparent from the following description when taken in conjunction 25 with the accompanying claim.

25 Referring to the drawings in which is shown a preferred embodiment of the invention,

Figure 1 is a perspective view of a sectional shoe tree with the invention applied thereto.

30 Figure 2 is an enlarged vertical sectional view of Figure 1.

Figure 3 is a sectional view taken substantially along the line 3—3 of Figure 2.

35 Figure 4 is a detailed exploded view of the connecting bar and the locking plunger, and

Figure 5 is a detail perspective view of the toe section.

40 Referring to the drawings, in which like numerals indicate like parts in the several views, 10 denotes a shoe tree preferably composed of the toe section 11 and the heel section 12, the upper adjacent portions of each section being cut out so as to form a recess 13.

45 The sections 11 and 12 are provided with longitudinal aligned openings 14 and 15, respectively, the opening 14 terminating in a vertical reduced recess or slot 16, that extends upwardly and medially to the cut-out portion 13.

50 A bar 17 is arranged to connect the sec-

tions 11 and 12, and is preferably formed with a reduced flat end portion 18 and a tubular end portion 19 (Fig. 4), the tubular portion 19 having a longitudinal elongated slot 20 in the upper surface thereof, which slot 55 is formed of opposed flanges comprising spaced curved sections 21 connected by straight sections 22. The flat end portion of the rod 17 fits within the recess 16 and is connected to the toe section by a pin 23, that 60 extends into a transverse opening 23' in the toe section 11 and through an opening 24 in the bar 17. The tubular portion 19 of the bar 17 is then introduced into the aligned openings 14 and 15, and the heel section 12 is permitted to be moved relative to the section 11 65 and maintained in any predetermined adjusted position relative thereto, so as to accommodate shoes of different sizes through the instrumentality of a locking plunger or stud 70 25 (Fig. 4), preferably formed with lateral projecting shoulders 26, positioned intermediate the ends of the plunger and a threaded reduced shank 27, that extends upwardly 75 from the shoulder. The plunger 25 is arranged to be positioned within a vertical opening 28, which communicates with the opening 15 in the heel section, while the shank 27 extends through the slot 20 in the bar 17, so that the shoulders 26 may engage the 80 underside of the opposed flanges formed by the slot 20. The plunger 25 adjacent the shoulders 26 is preferably formed with parallel flat sides 26' which register with the inner end of the slot 20 to permit the insertion and 85 removal of the plunger from the shoe tree. It will be seen that the plunger is movably secured in position by first being inserted into the opening 28 and the slot 20 when the sides 26' are arranged parallel with the slot 90 and is then moved to its locked position by being rotated so as to cause the shoulders 26 to engage the underside of the flanges 21 and 22. A coiled spring 29, which is mounted in the bottom of the opening 28, so as to abut against 95 the adjacent end of the bar 25, normally urges the shoulder 26 into engagement with the bar 17. The opening 28 terminates in an enlarged recess 30 (Fig. 3), in which extends the shank 27, so as to receive a handle or a 100

knob 31 that is threadedly connected thereto above the bar 17. The handle 31 extends outwardly from the cut-out portion 13 to a point about even with the horizontal plane of the upper surface of the sections 11 and 12, so that the tree may be conveniently packed or carried without having any parts protruding therefrom; a feature which is very essential in articles of this kind, especially when traveling. A supporting handle 32 in the form of a metallic ring or the like may be secured to the upper surface of the heel section 12 so as to facilitate the handling of the shoe tree.

The spring 29 normally tends to maintain the plunger 25 in locked engagement with the bar 17 so as to prevent relative movement of the sections 11 and 12. However, upon downward pressure being imparted to the handle 31, the plunger 25 will be moved downwardly into the opening 28 against the tension of the spring 29, thus releasing the engagement of the shoulders 26 with the sides of the slot 20, which permits the heel section 12 to be moved longitudinally relative to the section 11. When the parts have been moved the desired distance, releasing of the pressure on the handle 31 will cause the spring 29 to force the shoulders 26 again into locking engagement with the bar 17, thus positively securing the sections in any predetermined position as may be desired.

It is to be understood that the form of the invention herewith shown and described, is merely illustrative of a preferred embodiment, and that such changes may be made therein as fall within the purview of one skilled in the art without departing from the spirit of the invention, and the scope of the appended claim.

What I claim is:

A shoe tree of the class described comprising a toe section and a heel section, said sections having a cut-out portion and longitudinally aligned openings, a bar extending into said openings, means pivotally connecting one end of said bar to the toe section, said bar having a tubular portion provided with an elongated vertically disposed slot slidably mounted in the opening of said heel section, the sides of said slot having inwardly extending spaced flanges, said heel section having a vertically disposed orifice communicating with the longitudinal opening therein, a locking plunger mounted in said orifice and having a shoulder arranged to engage the underside of said flanges for maintaining the bar in fixed position relative to the heel section, said plunger having parallel flat sides adjacent said shoulders arranged to register with an end portion of the slot for permitting the insertion and removal of the plunger from the shoe tree, and a spring positioned in the bottom of said orifice for normally maintaining the shoulder in engagement with said slotted portion, said plunger having its ex-

posed end extending slightly above said cut-out portion whereby upon the depression of the plunger the shoulder is released from engagement with the bar to permit the movement of said sections relative to each other.

In testimony whereof I have hereunto set my hand.

OLIVER J. HOWE.
